UNITED STATES PATENT OFFICE.

HARRY DE FOREST MADDEN, OF NEWARK, NEW JERSEY, ASSIGNOR TO WESTINGHOUSE LAMP COMPANY, A CORPORATION OF PENNSYLVANIA.

STENCIL.

Application filed September 16, 1921. Serial No. 501,126.

To all whom it may concern:

Be it known that I, HARRY DE FOREST MADDEN, a citizen of the United States, and a resident of Newark, in the county of Essex and State of New Jersey, have invented a new and useful Improvement in Stencils, of which the following is a specification.

This invention relates to stencils employed in lettering and ornamenting articles, and it has for its primary object the provision of an improved stencil constructed to withstand the wearing action of the material employed to react with the surface of an article to be marked.

10 A further object is to provide a stencil with a resilient protective coating which prevents an operating or abrasive material from wearing away the small projecting ends and cross bonds created in the stencil body when a pattern is formed therein.

It has been found by experience that the life of a stencil is usually dependent upon its ability to withstand the wearing action of the material which is employed to score 25 the surface of the article to be inscribed. This is especially true of metal stencils, as the small ends and cross bonds are worn away at a very rapid rate, thus necessitating the closing down of the machines at frequent intervals during working hours to 30 make necessary stencil replacements. The loss due to the idleness of the machines also means a loss due to the idleness of the operators. These losses, when taken with 35 the cost of the large quantity of stencils required, increase the operative cost of the machines beyond a value commensurate with the results accomplished.

40 My invention contemplates the use of an improved stencil which materially reduces the cost of operation of a stenciling machine and which permits a larger number of articles to be marked before stencil replacements are required.

45 In the accompanying drawings, which form a part of this specification,

Fig. 1 is a top plan view of a selected stencil having a pattern formed therein;

50 Fig. 2 is a sectional view taken on the line II—II of Fig. 1;

Fig. 3 is a sectional view taken on the line III—III of Fig. 1; and

Fig. 4 is an elevational view showing, in

section, my improved stencil mounted in a stenciling machine.

Referring now to the drawings, the selected embodiment is of a stencil generally employed for marking or forming legends on the bulbs of incandescent lamps by having sand or other abrasive material blown against the stencil. The preferred construction of my improved stencil is best appreciated by reference to Figs. 2 and 3 wherein the stencil is shown as being composed of a flexible metal body 1 and a resilient member 2 affixed to the metal body in any desired manner. The resilient member, usually a sheet of rubber, may cover only a portion of the metal body but it is preferred to have it cover the whole surface, as illustrated.

A desired pattern is formed in the stencil by punching out certain portions thereof in the usual manner, and, for the purposes of this description, the pattern takes the form of one of the letters of the alphabet. The punching operation is usually performed after the resilient coating has been affixed to the metal body. If desired, however, the metal body may be punched first and the resilient member affixed after given openings have been formed therein.

In manufacturing the stencils, the formation of the patterns create small projecting ends 3 and connecting or cross bonds 4 which are very small in size in relation to the other portions of the stencil. Stencils heretofore manufactured have not had a protecting means for these small ends and bonds, and, consequently, they have been rapidly worn away by the abrasive material, thus enlarging the openings of the pattern to such an extent that the markings on the surface of articles become blurred and unintelligible.

In providing a protection of resilient nature to one side of the metal body, the small ends and bonds are not subjected to the scoring action of the abrasive material, and, therefore, clear-cut patterns are formed on the articles, and, in addition, the life of the stencil is materially increased. It will be appreciated that, by increasing the life of the stencil, a stenciling machine may be maintained in continuous operation for a materially longer time, thereby reducing the idle time of machines and operators.

The use of these long-life stencils permits replacements to be made during the shutdown hours of the factory.

The manner in which the improved stencil is mounted in a stenciling machine is illustrated in Fig. 4. A portion 5 of a machine is shown having therein openings 6 through which ends 7 of the stencil may be inserted and bent to firmly hold the stencil in normal curved position. The unprotected surface of the stencil is engaged by a lamp bulb 8 and the flexibility of the metal permits the stencil to conform to the curved surface of the bulb. The cutting or abrasive material 15 may be brought into contact with the lamp bulb and stencil in any desired manner but I prefer to have it blown by air under pressure through guiding conduits 9. The particles of the abrasive which pass through 20 the stencil openings score the surface of the lamp and form the desired marking or pattern thereon. The particles which do not make contact with the lamp bulb are buffered by the rubber and thus are not permitted 25 to wear or affect the metal body.

The use of resilient coatings is much more desired than a harder substance, such as fibre, as the harder substance reduces the flexibility of the stencil, thus preventing the 30 article to be marked from being moved into a firm and complete contact with the stencil. I have found that, by employing a stencil of the improved construction, the length of life of the stencil is increased about 300% 35 and I am thus enabled to maintain each stenciling machine in continuous operation during full working hours.

Modifications and changes in the construction of the stencils will be apparent to those 40 skilled in the art, but such modifications and changes are considered as being within the scope of my invention, as defined in the appended claims.

What is claimed is:

45 1. A removable stencil having a pattern formed therein and having a resilient mate-

rial adjacent to the edges of said pattern and adapted to arrest the wearing away of the pattern by a cutting material.

2. A removable stencil for use in marking articles by an abrasive material comprising a metal body having a pattern formed therein and a resilient material affixed to the exposed surface of said body for preventing said abrasive material from making contact 55 with said metal body.

3. A removable stencil for use in marking articles by sand blast comprising a metal body having a pattern formed therein and a resilient material affixed to the exposed surface of said body for preventing an abrasive material from making contact with said body.

4. In a rigid removable stencil for marking articles by sand blast, a resilient layer 65 upon the exposed surface of said stencil for protecting those portions of the stencil adjacent to the openings therein from the action of a cutting material.

5. A stencil comprising a rigid metal body 70 having openings therethrough and a rubber coating associated with one surface thereof and having openings therein corresponding to the openings in said body, said coating being adapted to prevent an abrasive material from making contact with said body, said stencil being adapted for removal after 75 use.

6. A stencil adapted for use in sand-blast machines composed of a thin rigid removable metal body having a symbol punched therein and a rubber coating affixed to said body and having openings therein corresponding to the openings in said body, said rubber being adapted to absorb the shock 80 of the sand particles impinging thereagainst, whereby wear upon the edges of the symbol is materially reduced.

In testimony whereof, I have hereunto 85 subscribed my name this 15th day of September 1921.

HARRY DE FOREST MADDEN.
